UNITED STATES PATENT OFFICE.

ARTHUR C. HOPKINS, OF NILES, MICHIGAN, ASSIGNOR TO NATIONAL STANDARD COMPANY, OF NILES, MICHIGAN, A CORPORATION OF MICHIGAN.

BRAIDING CARRIER.

Application filed May 26, 1923. Serial No. 641,613.

To all whom it may concern:

Be it known that ARTHUR C. HOPKINS, a citizen of the United States, residing at Niles, in the county of Berrien and State of Michigan, has invented a new and useful Improvement in Braiding Carriers, of which the following is a specification.

This invention relates to braiding carriers and is particularly adapted to be used in connection with machines for braiding steel wire cables and the like, and is fully described in the following specification and shown in the accompanying drawings, in which:

15 Figure 1 is a side elevation of a carrier embodying the invention;

Fig. 2 is a front elevation of the same; and

20 Fig. 3 is a transverse section through the spring for retracting the sheave.

The embodiment illustrated comprises the frame 10 which is integral with spindle 11 which is adapted to be mounted for rotation upon the table of a braiding machine not shown. For the purpose of this application, it is sufficient to state that as these automatic take-ups are revolved about each other during the braiding operation, the carrier moves alternately toward and from the center of the machine toward which the wire is fed, thereby necessitating the use of some automatic means for taking up the slack in each wire A which is used in the braiding operation.

35 The wire A is wound upon a reel 12 which is journaled upon an axle 13 which is carried by a frame 10 and bracket 14. The wire A then passes over the sheave 15 which is journaled on a pin 16 and passes down under the movable sheave 17 and thence out through the guide 18.

The sheave 17 is journaled upon a pin 19 which is carried by a bifurcated yoke 20 which is secured to a flexible member 21 which is secured to a cylinder 22 (see Figure 3) which is journaled upon a pin 23. A spiral spring 24 having one end secured to the pin 23 and the other end to the inside of the cylinder 22, is so wound as to place the flexible member 21 under tension. Guides 25 are placed on each side of the sheave 17 and have slots 26 adapted to receive the ends of the pins 19.

At the side of the reel 12 is a brake sheave

27 which is journaled on the pin 13 and has a lug 28 which engages a hole in the end of the reel 12. This sheave is grooved to receive a brake band 29 one end of which is secured to the adjusting screw 30 while the other is carried by the end 31 of the lever 32 which is fulcrumed at 33. This lever is normally held in the position shown in the braking position by means of the spring 34. The outer end 35 of the lever 32 is bifurcated and extends on each side of the guides 25 so as to engage the outer ends of the pins 19 as the sheave 17 is raised by the tension of the wire A to the upper end of the slot 26.

From the foregoing, it will be apparent that when the tension on the wire lifts the sheave 17 against the action of the spring 24, the pin 19 will engage the end 35 of the lever 32, thereby momentarily releasing band 29 from the brake sheave 27, thereby permitting the reel 12 to feed the wire A under the tension of the spring 24 until the sheave 17 has again moved down to a point where the shaft 19 is no longer in contact with the end 35 when the spring 34 will again move the brake lever 32 into braking position and the reel 12 will cease feeding until the brake lever 32 is again released.

The tension on the spring 24 may be varied by turning the shouldered bolt 23 and it may then be locked in adjusted position by means of the lock-nut 23a.

It will also be noted that the bolt 23 is carried by a frame 36 which is slidable on pins 37 which have heads 38. The wire A holds this frame 36 in the raised position shown, in which it is above the depressions 39 (see Fig. 2) in the side of the frame members 10 and 14. A fixed member (not shown) on the table of the machine of which this is a part normally passes through this depression as the bobbin is rotated. If the wire A breaks or the bobbin is empty, the frame 36 falls and engages the members (not shown) and through mechanism on the table (not shown) causes the braiding machine to stop.

While I have shown and described certain embodiments of my invention, it is to be understood that it is capable of many modifications. Changes therefore in the construction and arrangement may be made without departing from the spirit and scope of the invention as disclosed in the appended

claims, in which it is my intention to claim all novelty inherent in my invention as broadly as possible in view of the prior art.

I claim:

- 5 1. In a braider, a carrier for feeding wire and the like comprising a frame, a reel journaled in said frame, a brake operably connected to said reel, a sheave over which a loop of the wire runs, a spiral spring, a 10 cylinder enclosing the same, a flexible member connecting said cylinder and sheave for retracting the latter, said sheave being movable to engage a part of said brake to release the same when the sheave is drawn against the action of its spring, and a spring for 15 normally setting said brake release, said sheave being movable parallel to the wire leaving said sheave.
2. In a braider, a carrier for feeding wire and the like comprising a frame, a reel journaled in said frame, a brake operably connected to said reel, a movable sheave over which a loop of the wire runs, yieldable means for holding said sheave against said 25 loop, a spring pressed lever connected to the band of said brake, said sheave being mov-

able by the tension of the wire and against the action of its spring and carrying a member adapted to engage said lever to cause the brake to be released, the movement of 30 the outer end of said lever necessary to release the brake being relatively large, and said sheave being movable parallel to the wire leaving said sheave.

3. In a braider, a carrier for feeding wire and the like comprising a frame, a reel journaled in said frame, a brake operably connected to said reel, a movable sheave over which a loop of the wire runs, a spiral spring, a cylinder enclosing the same, a flexible member connecting said cylinder and sheave for retracting the latter, yieldable means for holding said sheave against said loop, a spring pressed lever connected to the band of said brake, said sheave being movable by the tension of the wire and against the action of its spring and carrying a member adapted to engage said lever to cause the brake to be released; the movement of 40 the outer end of said lever necessary to 45 release the brake being relatively large.

ARTHUR C. HOPKINS.
